UNITED STATES PATENT OFFICE.

JOSEPH POZNANSKI, OF NEW YORK, N. Y., ASSIGNOR OF ONE-HALF TO
HENRY M. HAAR, OF SAME PLACE.

VENT FOR CASKS.

SPECIFICATION forming part of Letters Patent No. 289,555, dated December 4, 1883.

Application filed September 13, 1883. (No model.)

To all whom it may concern:

Be it known that I, JOSEPH POZNANSKI, of the city and county of New York, in the State of New York, have invented a new and useful 5 Improvement in Vents for Casks, of which the following is a specification.

In order to operate successfully the valve of a beer-vent, while it must be free to open for the admission of air when necessary in 10 drawing the beer from the cask, it must close absolutely tight, when the drawing ceases, else all the gas in a keg will escape after the vent is driven in, and the valve must close thus tightly even when the keg to which the vent 15 is applied is tilted as kegs usually are when drawing beer from them.

The invention consists in novel features of construction and combinations of parts, hereinafter particularly described, and pointed 20 out in the claims, whereby the desired ends are attained.

In the accompanying drawings, Figure 1 is a vertical section of my improved vent, and a portion of a cask-stave, wherein it is secured. 25 Fig. 2 is a side view of the vent, also including a portion of the stave; and Fig. 3 is an inverted plan of the vent, the valve-box and valve being removed.

Similar letters of reference designate corresponding parts in the three figures.

A designates the stave, and B designates the vent-plug or body of the vent inserted therein. It consists of a piece of cast-iron or other material having a laterally-extending 35 branch or arm, B', the outer end of which turns downward, and has screwed upon it a valve-box, C, a packing-ring, a, of rubber or other material being used between the valve-box and the part on which it screws to form 40 a tight joint. The valve-box C has a central aperture, b, and a valve-seat, c, surrounding the same on the inner and upper side of the said box.

D designates the valve of the vent, here 45 shown as consisting of a flat disk seating on the seat c. The valve is provided with a stem, D', which extends downward through the aperture b considerably beyond the valve-box C, and on the projecting portion of this stem

is a nut or collar, d, larger in size than the 50 aperture b. The projecting portion of the stem D' may, if desired, be protected by a guard, E, attached to the valve-box C, as shown in Fig. 1.

When the beer-vents are in use they are 55 commonly inclined from the perpendicular as the kegs or barrels to which they are applied are tilted, and it will be seen that air will be admitted through the aperture b if the valve D is simply canted or raised at one side off 60 its seat without the valve being bodily lifted. As to cant the valve will require less suction within the keg or cask than to lift it bodily, it will be seen that the valve will be very sensitive to any diminution of pressure in 65 the keg or cask. In case the valve-seat c should become clogged with saccharine or other solid matter, so as to prevent the valve D from closing tightly, the valve may be turned by grasping its stem on the nut or collar 70 d with the fingers, and a new seat formed on the saccharine or solid matter. By providing the stem D' with a nut or collar, d, larger than the aperture b the valve is prevented from being lost when the valve-box C 75 is taken off for cleaning or for any other purpose. In order that the valve D shall not close the end of the branch or arm B', when raised against it, I preferably form in the end of the branch or arm a groove, e, (best shown 80 in Fig. 3,) which affords a clear passage for air, even if the valve be pressed up tightly against the end of said branch or arm.

What I claim as my invention, and desire to 85 secure by Letters Patent, is—

1. The combination, with a vent-plug having a laterally-extending branch or arm, of a valve-box containing a valve-seat, applied to the end of said branch or arm, a valve fitted to said seat, and having a stem projecting 90 downward through and beyond the valve-box, so that it may be taken hold of for the purpose of manipulating the valve, and a guard attached to the valve-box, and protecting the projecting stem portion, substantially as herein described.

2. The combination, with the vent-plug B and its branch or arm B', of the valve-box C,

formed with the aperture *b* and valve-seat *c*, and the disk-valve *D*, having the stem *D'* projecting through and beyond the aperture *b*, and there provided with a nut or collar larger than said aperture to confine the valve to the box, substantially as herein described.

3. The combination, with the vent-plug *B* and its branch or arm *B'*, having in the end the groove *e*, of the valve-box *C*, screwed upon the exterior of the said branch or arm, and

constructed with the apertures *b* and valve-seat *c*, and the valve *D*, working between said seat and the grooved end of the branch or arm *B'*, and having a stem, *D'*, projecting through the aperture *b*, all substantially as herein described. 15

JOS. POZNANSKI.
